UNITED STATES PATENT OFFICE.

ELIAS A. BLICKENSTAFF, OF NORTH MANCHESTER, INDIANA.

TIE-STRAP HOLDER FOR HARNESS.

SPECIFICATION forming part of Letters Patent No. 243,840, dated July 5, 1881.

Application filed May 12, 1881. (Model.)

To all whom it may concern:

Be it known that I, ELIAS A. BLICKENSTAFF, of North Manchester, county of Wabash, and State of Indiana, have invented certain useful 5 Improvements in Tie-Strap Holders for Harness, of which the following is a specification.

Figure 1 is a side elevation of my improvement. Fig. 2 is an edge elevation of the same.

The object of this invention is to facilitate 10 the securing and releasing of the straps for harnesses.

The invention consists in the combination, with a harness-terret, of a rigid base-bar, an elastic arm, and a spring, as will be hereinafter fully described.

A represents a terret, which is provided with a screw to be screwed into the harness-saddle in the usual way.

Upon the lower side of the shank of the terret A is formed a bar, B, the lower end of which is provided with a pin or screw, C, to enter the harness-saddle and prevent the holder and terret from turning when inserting and removing the tie-strap.

25 Upon the side of the ring of the terret A is formed an elastic arm, D, which is arranged directly over the base-bar B, and which can be curved, as shown in Fig. 1, or made in any other desired shape, as the style of the harness-trimmings may require.

Upon the outer end of the arm D is formed, or to it is attached, the outer end of a spring, E, which extends inward directly above and parallel with the bar B.

35 With this construction the tie-strap is secured by passing it into the space between the base-bar B and the spring E, when the elasticity of the spring E will hold the said tie-strap securely in place. With this construction, also, the elasticity of the spring E and

45 arm D will allow tie-straps of different thickness to be readily inserted in the holder. When the tie-strap is inserted in the outer end of the holder it presses the outer ends of the arm D and spring E upward, and as the said strap is forced farther inward it forces the inner end of the spring E upward, which tends to force the outer ends of the spring E and arm D downward, so as to prevent the said strap from working outward, the tendency being to cause the said tie-strap to work inward, so that it will be held securely.

55 The bar B and arm D can be formed in one piece with the terret A, or it can be formed separate and held in place by the said terret. The latter construction allows the holder to be applied to a harness that does not have terrets.

If desired, a second spring, E, can be formed upon or attached to the base-bar B, and arranged parallel with the first spring E; but 60 the construction first described is preferred, as being simpler, cheaper, and equally effective.

The base-bar B can be omitted and the tie-strap inserted beneath the spring E, so as to be between the said spring and the harness-saddle, where it will be securely held.

Having thus fully described my invention, I claim as new and desire to secure by Letters Patent—

70 In a tie-strap holder, the combination, with the terret A, of the rigid base-bar B, the elastic arm D, and the spring E, substantially as herein shown and described, whereby the tie-strap can be readily inserted and withdrawn, and will be securely held, as set forth.

ELIAS A. BLICKENSTAFF.
